PULVERIZING AND SEPARATING MACHINE

George Holt Fraser, Brooklyn, N. Y.

Application June 15, 1932, Serial No. 617,395
Renewed April 15, 1939

16 Claims. (Cl. 83—45)

This invention relates to combined pulverizing mills and air separators, and aims to provide certain improvements therein.

One such device is shown in my Patent No. 1,499,516, dated July 1, 1924, and others are shown in my Patents Nos. 1,834,094 and 1,834,095, dated Dec. 1, 1931. The devices disclosed in these patents were finishing mills in which all the material fed into the mill must be fully pulverized, as no provision was made in them for the discharge of uncrushed material.

This invention aims to improve combined pulverizing and air separating mills, and to this end makes provision therein for the discharge below the return current passage thereof of uncrushed material therefrom, and provides them with various other features of improvement, all of which in their preferred form and utilization will be more fully set forth with reference to the accompanying drawings, in which

Fig. 1 is a side elevation, partly in vertical axial section of one type of combined pulverizer and air separator provided with the preferred form of my present improvements;

Fig. 2 is a fragmentary plan view thereof partly broken away to show fragments of the drive gears, valve, fan blades and crushing chamber, and

Fig. 3 is a fragmentary horizontal section thereof, cut approximately on the planes of the lines 3—3 in Fig. 1.

In the type, shown in Figs. 1, 2 and 3, of a combined mill and air separator with which the preferred form of my present improvements is shown as availed of,

A is a die or crushing element having an inner annular crushing face disposed around a vertical axis;

B are rotatable crushing rolls or elements within and eccentric of and each having a peripheral crushing face reciprocal to said face, for crushing material between said faces;

C is a disc or distribution means, for distributing material to be crushed to said faces;

D is a supply means or vertical conduit having an orifice above said disc, for supplying said material thereto;

E is a crushing chamber encircled by said die;

F is a rotary means for rotating said parts;

G is a bearing or support means or frame for said parts;

H is an outer casing or housing spaced around said die and chamber;

I is a blower means or fan blades within said casing;

J is a settling chamber or current passage within said casing;

K is a fine material intercepting means or filter within said casing;

L is a dust chamber below said filter;

M is a dust outlet from said dust chamber;

P is an annular casing above the die A and around and enclosing the chamber E and spaced concentrically within the casing H;

Q is an upper current and fine material discharge outlet from the chamber E to and in communication with the chamber J;

R is an annular casing below the die A and around and enclosing the chamber E;

S is a lower current inlet to the chamber E and in communication with the chamber J;

T is a vertically adjustable annular valve above the outlet Q;

U is an adjusting screw for the valve T;

n2 is an open dropper outlet from the chamber E, inwardly of and extended through the inlet S and in communication from below the crushing elements, through said inlet, to below and externally of said chamber, for dropping coarser material from the latter;

W is a sustainer wall below the dropper outlet n2 and spaced below the inlet S, for receiving and sustaining below the latter said dropped material;

X is a return current passage below the inlet S and above the wall W, and in communication from the chamber J, through said inlet, with the chamber E, for returning current to the latter;

A' is an uptosser means inwardly of the inlet S and in communication therethrough from above the wall W to within the chamber E, for uptossering through said inlet and returning to the crushing elements within said chamber uncrushed material sustained on said wall, and

S' is a chamber for the valve T.

These parts may be any usual or suitable parts for crushing material within the crushing chamber E, affording an endless current passage up through and down around the latter, and for causing a separating current to upfloat fine material from the crushing elements within the crushing chamber into the settling chamber, and to return through the return current passage to the lower inlet, and for permitting coarser material to drop below the crushing elements and through the returning current from the crushing chamber E on to the bottom wall W of the return current passage X, and for uptossering uncrushed material from said wall to said elements, according to the usual principle of operation

common to combined pulverizers and air separators.

As shown—

- 5 *a* are beams or support means for the frame *G*;
- b* are bolts connecting the die *A* and casings *P* and *R*;
- c* are spoke means between and connected with the casing *P* and the rotary means *F*, and affording a rotation connection therebetween;
- 10 *d* is a hub for the spoke means *c*;
- e* is a vertical tubular shaft for the spoke means *c*;
- f* is a rockable collar on the shaft *e*;
- g* is a bearing for the shaft *e*;
- 15 *h* is a bevel gear keyed to and carrying the shaft *e* from the bearing *g*;
- i* is a bevel pinion meshing with the gear *h*;
- j* is a tubular shaft for the pinion *i*;
- k* is a pulley for the shaft *j*;
- 20 *l* are outwardly swingable arms on the outer ends of which the rolls *B* are journaled respectively so as to bear against the inner face of the die *A*;
- m* is a ring hub on which the inner ends of the 25 arms *l* are pivotally mounted;
- n* is a vertical tubular shaft within the shaft *e* and around the pipe *D* and carrying the hub *m*;
- o* is a rockable collar on the shaft *n*;
- 30 *p* is a bevel gear keyed to and carrying the shaft *n*;
- q* is a bearing for the gear *p*;
- r* is a beveled pinion rotating the gear *p*;
- s* is a horizontal shaft within the shaft *j* and carrying the pinion *r*;
- 35 *t* is a pulley for the shaft *s*;
- u* are springs outpressing the arms *l* and rolls *B* toward the die *A*;
- v* are screws for adjusting the tension of the springs *u*;
- 40 *w* are spoke means for the fan blades *I*;
- x* is a fan hub carrying the fan spokes *w*;
- y* is a vertical tubular shaft around the shaft *e* and carrying the hub *x*;
- z* is a bevel gear fastened to the shaft *y*;
- 45 *a'* is a bearing for the gear *z*;
- b'* is a bevel pinion rotating the gear *z*;
- c'* is a horizontal tubular shaft around the shaft *j* and carrying the pinion *b'*;
- d'* is a pulley on the shaft *c'*;
- 50 *e'* is a lower wall of the frame *G*, below and carrying the bearing *a'*, which carries the gear *z*, which carries the bearing *g*, which carries the gear *h*, which carries the bearing *q*, which carries the gear *p* in such manner that each of these gears and its vertical shaft and the parts carried by the latter respectively, is revolubly supported from said frame;
- f'* is a tubular partition around the shaft *y* and depended from the frame *G* above the spokes *w*, and inwardly defining the discharge passage *Q* thereabove;
- 60 *g'* is the upper outer wall of the housing *H*, shown in the form of a truncated cone spaced from and around the casing *P*;
- 65 *h'* is an annular fanway or space between the casing *P* and the wall *g'* and in which the blades *I* revolve;
- i'* are the inner edges of the fan blades *I*, shown as upstood above the spokes *w*;
- 70 *j'* are the horizontal lower inner edges of the fan blades *I*, shown as cutaway above and around the die *A*;
- k'* is a conically recessed annular bottom flange on the frame *G* and around and receiving the upper end of the wall *g'*;
- l'* are bolts fastening the wall *g'* in the flange *k'*;
- m'* is the lower wall of the housing *H*, shown as an inverted conical member connected base to base on the conical member *g'*;
- n'* are bolts connecting the members *g'* and *m'*;
- o'* are support brackets within the wall *m'*;
- p'* is the top wall for the filter *K*;
- q'* are the inclined lower ends of the filter *K*;
- s'* is an elevator for supplying material to be pulverized to the pulverizer;
- t'* is a conveyor extended from said elevator to the hopper of the pulverizer;
- w'* is a hopper carrying the supply pipe *D* from the frame *G*;
- x'* is a cover for the frame *G*;
- y'* is a vertical conduit through the hopper *w'* above and coaxial with and in communication with the pipe *D*, for vertically precipitating coarser material toward the latter;
- z'* is a lateral conduit in the hopper *w'* and in communication with one side of said vertical conduit, for laterally supplying inverted material thereto at said side thereof;
- 25 *a2* is a cover for the hopper *w'*;
- b2* is a sustainer wall within the conduit *y'* and opposite and spaced from the conduit *z'*, adapted to laterally sustain opposite the latter coarser material precipitated through the former;
- c2* is a belt driven by the shaft *c'* for driving the conveyor *t'* therefrom;
- d2* is a conveyor pulley driven by the belt *c2*;
- e2* is a conveyor shaft driven by the pulley *d2*;
- 30 *f2* are bevel gears driven by the shaft *e2*;
- g2* is an elevator pulley driven by the bevel gears *f2*;
- h2* is an elevator belt driven by the pulley *g2*;
- i2* is an elevator pulley driven by the belt *h2*;
- 35 *j2* is a gas inlet to the hopper *w'*;
- k2* is a gas chamber within the hopper *w'* and in communication with the inlet *j2*;
- l2* is a gas conduit within the hopper *w'* and around the wall *b2* and in communication from the chamber *k2* to the vertical conduit *D*;
- 40 *m2* is an annular gas chamber between the distributor *C* and the wall *W*, for collecting gas therebetween;
- o2* are tubular gas conduits in communication from the gas chamber *m2* up through and above the distributor *C*, for up-passing gas past the latter;
- p2* is a vertical annular gas conduit around the pipe *D* and within the shaft *n*, and in communication with the conduits *o2*, for up-passing gas therefrom;
- 45 *q2* is an annular gas chamber around the hopper *w'* and in communication from the conduit *p2* to the chamber *k2* for conducting gas therebetween;
- r2* is a gas pipe in communication from below the wall *e'* of the frame *G* to within the chamber *k2* in the hopper *w'*, for conducting gas therebetween;
- 50 *s2* is an annular gas chamber in the frame *G* and in communication above and around the wall *g'* with the fanway *h'*, for receiving gas above and from the latter and conducting it to the pipe *r2*;
- t2* is a valved gas pipe in communication with the pipe *r2*, for controlling supply thereto of, or removing therefrom, gas;
- 55 *u2* is a valve for the pipe *r2* for controlling flow therethrough;
- 60 *75*

5 v_2 is an annular gas trap around the outlet Z , for collecting gas therearound;

10 w_2 is a gas outlet from and in communication with the trap v_2 , for removing gas therefrom;

15 x_2 is a gas pipe in communication from the gas trap v_2 to the gas chamber s_2 , for transferring gas therebetween;

20 y_2 is a gas supply pipe in communication with and for supplying gas to the pipe x_2 ;

25 z_2 are valves for controlling flow of gas through the pipes x_2 and y_2 .

These parts may be any conventional parts for the supply and distribution of material to the crushing elements, and for supporting and operating the latter, and the blower means, and other parts of the device.

As shown the shaft n movably suspends and rotates the distributor C , rolls B , and up-tossers A' , and the shaft e movably supports and rotates the die A and the casings P and R connected therewith, and the shaft y supports and rotates the fan blades I , and each of these parts is revolvably suspended from the frame G and relatively revolvable within and concentric of the housing H , which is shown as non-rotatively depended from the frame G .

In such pulverizers the wall W has constituted a bottom wall for the return current passage X and a retainer wall for retaining within the pulverizer coarser material, until all of such material was returned to the crushing elements by the up-tossers A' and completely pulverized, a construction endangering clogging of the pulverizer in case the rate of feed to it exceeded the rate at which it could finish pulverization of the material; and the wall under the dropper outlet, for receiving coarse material dropped therefrom, has extended across the zone of precipitation from said outlet, and has supported and rotated the die from across the space below said outlet, and has been molested by droppings from the latter.

My present invention aims to avoid such clogging and molestation, and improve the construction and operation of combined pulverizers and separators, and to this end provides the following features of improvement therein:

According to one feature my present invention provides such a combined pulverizer and separator with a coarse material discharge means below said dropper outlet and below the zone of the returning current, for receiving coarser material dropping through said outlet and discharging it from below said zone to externally of the pulverizer, for accomplishing which purpose,

Y is a coarse material discharge means below the dropper outlet n_2 and the wall W and the return current passage X , and extended therefrom in the form of an inverted truncated cone having an upper end spaced around the periphery of the wall W and in communication around said periphery with the dropper outlet n_2 and the passage X , which cone is disposed inwardly of the dust chamber L and concentrically within the housing H , and is in communication from within to without the latter, and receives coarse material from and around the wall W and conveys and discharges it below the latter, and inwardly of the dust chamber, through a discharge outlet Z extended from said cone to externally of the housing H , and shown as connected to the elevator s' for returning coarser material to the hopper w' .

As shown the cone Y is a foraminous screen, 75 for screening material of intermediate fineness

from such coarser material, and a receptacle N is provided for such screenings, in the form of an inverted cone, having an imperforate wall u' under and around the cone Y and spaced inwardly of and concentrically of the wall m' , for receiving such intermediate material and downwardly conveying it inwardly of the dust chamber and across the latter to externally thereof, through an outlet O in communication from the chamber N to externally of the housing H , and the cone u' is shown as carried from the cone m' by the brackets o' , and the cone Y is shown as yieldably carried from the cone u' by springs v' , and the upper ends of the cones u' and Y are shown as spaced inwardly of and surrounded by the filter K . In this construction the cones Y and u' constitute complementary parts of externally extended discharge means adapted to classify said dropped material into coarser and intermediate grades, and to freely separately discharge these grades to externally of the housing.

Another feature of my invention avoids molestation of the connection between the die A and the casings P and R and the overhead support and rotation means therefor by disposing said connection entirely above the zone of distribution of said material, connecting it to said parts above said zone, and constructing it to support and rotate said parts from said overhead support and rotation means from without and above the space below said dropper outlet and the zone of precipitation of coarse material from the latter, to accomplish which I make the spoke means c circumferentially spaced and extend them across the upper current outlet Q in such manner that the separating current may discharge through the spaces between them, and dispose them above the die A and rolls B and distributor C and above the zone of distribution and entirely without the space below the dropper outlet n_2 , and connect them to the die above the latter, preferably by upwardly inclining the spoke means from the hub d toward and connecting them to the upper part of the casing P , and connecting the latter to the die A and the casing P by bolts b therebetween, in such manner that molestation by such connection of the crushing chamber and dropper outlet therebelow is avoided.

Another feature of my invention aims to facilitate discharge of coarse material below the dropper outlet n_2 and below the current passage X , and to this end I preferably make the bottom wall W of the latter as a rotatable disc opposite and spaced below said dropper outlet a distance equal to the height of said passage, in communication from the latter to externally thereof and constructed to receive dropped material below said passage and to rotatably discharge it from thereunder to externally thereof, preferably as shown by suspending and rotating it from the distributor C , and constructing it as a disc the outer periphery of which is inwardly of and spaced from and in communication with the external discharge means Y , in such manner that rotation of the bottom wall W centrifugally discharges material thereon into the cone Y , for scraping which the wall W is preferably provided with and rotates a scraper r' inwardly of and adjacent the cone Y and extended above the latter within and adjacent the filter K .

Another feature of my invention preferably provides for rotatably resisting current leakage

around the cones Y and u' and below the filter K, to accomplish which I preferably provide a downwardly and outwardly inclined annular closure means or shelf or valve V under the return current passage X and the inclined lower ends of the filter K and across the space between the latter and the open upper ends of the cones Y and u', which valve is preferably carried and rotated from the wall W by the scrapers r', and resists upflow of current from the dust chamber L therearound.

Another feature of my invention provides for limiting the rate of external discharge of uncrushed material to a predetermined depth of such material sustained by the wall W, and this is preferably accomplished by spacing the up-tossers A' a distance above said wall equal to said depth, to the end that they may up-toss or return to the pulverizing elements only such material in excess of such depth as is sustained by said wall, so that centrifugal discharge of dropped material from the wall W may be limited to that within the spaced distance between said wall and said up-tossers.

Another feature of my invention provides for returning from the wall W to the pulverizing elements larger material than it is desired to centrifugally discharge from such wall, and this is preferably accomplished by spacing between the latter and the up-tossers A' inward conveyor or inpusher means B', shown as carried by and rotatable with the casing R and depended outwardly of and below the inlet S and inwardly across the dropper outlet n2 and the wall W to and in communication with a receptacle or grit pocket C' centrally of and carried by the wall W, in such manner that the inpushers B' will inwardly convey material from a spaced distance above the wall W into the pocket C', while permitting said wall to rotatably discharge material thereon below said inpushers, and by providing a screw elevator means D' in communication from the pocket C' to a return passage F' below the distributor C and above an annular centrifugal means G' rotatable therewith and around the casing H' rotatable with the distributor G' and in the form of an inverted truncated cone the smaller lower end of which is in communication with the pocket C' and the upper end of which opens into the passage F', in such manner that material in the pocket C' will be elevated therefrom by the screw D' and casing H' to the passage F', through which it will be outwardly projected by the annular distributor G' toward the inner face of the die A' against which it may be further pulverized by the rolls B.

Another feature of my invention provides for adjustably controlling infeed of uncrushed material through the lateral leg z' of the hopper w' by the vertical descent of material through the vertical leg y' of the latter, and this is preferably accomplished by making the wall b2 adjustable relatively to said lateral leg, as by constructing it with relatively movable inner and outer walls which are spaced to afford the gas passage l2 between them and are relatively circumferentially movable to adjust the width of the baffle which the partition b2 affords opposite the fresh feed inlet z'.

In the construction shown the lower ends I' of the fan blades I are inclined for downwardly impelling the current discharged by them, and a ring of filter troughs J', is mounted around the die A and filter K and inwardly of the ends I' of the fan blades, and is covered by a flange K' car-

ried by the die for resisting leakage between it and said troughs. As shown the outlets M and O are closed by gravity valves L'.

In operation with the construction shown uncrushed material dropping from the crushing elements will fall through the returning current to and be sustained on the wall W, by which it will be rotatably outwardly moved under the return current passage X and pass below the latter and around the periphery of the wall W into the cone Y, by which it will be downwardly and outwardly discharged from below the returning current to externally of the latter and the housing H.

The up-tossers A' will limit the rate of discharge from the wall W to such material sustained by the latter as is below the spaced distance between the up-tossers and said wall, and will return to the crushing elements material above said distance. The inpushers B' spaced between the up-tossers A' and the wall W, will inwardly convey part of the material sustained on said wall therebetween, and the receptacle C' will collect such part of said material, which will be elevated by the screw D' through the hopper H' to the annular distributor G', by which it will be redistributed to the crushing elements. Support and rotation of the pulverizing elements will be effected without molestation of the zone of precipitation of uncrushed material from the dropper outlet.

It will be understood that my invention is not limited to the particular details of construction, use, arrangement, or combination of parts, set forth as constituting its preferred form, since it may be availed of, in whole or in part, according to such modifications of these as circumstances, or the judgment of those skilled in the art, may dictate, without departing from the spirit of the invention.

What I claim is:

1. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, rotary material upifters inwardly of said die and above said wall, for up-tossing uncrushed material from said wall toward said die, and a rotary refeeder above said upifters and in juxtaposition thereto to receive and refeed such uplifted material, for refeeding such dropped material.

2. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, rotary inpushers above and adjacent said wall, for inwardly pushing such uncrushed material over said wall, and a rotary refeeder above said inpushers, for receiv-

ing and refeeding such inpushed material to said die.

3. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, inward conveyor means below said die and above said wall for inwardly conveying such uncrushed material falling from said die, and rotary refeeder means inwardly of said conveyor means for receiving and refeeding such inwardly conveyed material to said die.

4. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, inward conveyor means below said die and above said wall for inwardly conveying such uncrushed material falling from said die, and uplifter means inwardly of said inward conveyor means for receiving and uplifting said inwardly conveyed material into said die.

5. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, and classifier means intermediate said wall and said die for classifying such dropped material, comprising an upper inpusher for refeeding coarser dropped material and a lower discharger for discharging fine dropped material as tailings, and a tailings receiver conveyor for receiving and conveying such tailings.

6. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, inward conveyor means below said die and above said wall for inwardly conveying said uncrushed

material falling from said die, and a rotary upwardly and outwardly flared refeeder inwardly of and spaced from said die, in communication with said conveyor means and in communication therefrom to inwardly of said die, for refeeding such uncrushed material from said wall to said die.

7. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, inward conveyor means below said die and above said wall, for inwardly conveying uncrushed material falling from said die, and a spiral uplifter above said wall and spaced inwardly of said die, in communication with said conveyor means and in communication therefrom to inwardly of said die, for refeeding such uncrushed material from said wall to said die.

8. In a pulverizer, a main frame or casing, an annular horizontal die therein for discharging fine material, and dropping uncrushed material as tailings, carried by said frame and having an internal annular crushing face, a rotatable crushing roll within and eccentric of said die and having a peripheral crushing face toward said face for crushing material between said faces, supply means for supplying material to be crushed by said faces, drive means for rotating said roll, a material sustainer wall below said die, for receiving and sustaining such uncrushed material dropped from said die, inward conveyor means below said die and above said wall, for inwardly conveying said uncrushed material falling from said die, an uncrushed material receptacle inwardly of and encircled by said wall, in communication with said conveyor means and adapted to receive therefrom such uncrushed material, and a refeeder above and in juxtaposition to said receptacle, in communication therefrom and in communication therefrom to inwardly of said die, and adapted to receive said uncrushed material from said receptacle, and to refeed said uncrushed material into said die.

9. In a current recirculation pulverizer, a casing enclosing a settling chamber, means mounted within and in spaced relation to said casing enclosing a crushing chamber, having an upper current outlet and a lower current inlet in communication with said settling chamber, and affording an endless current passage up through, out over, and down around, said crushing chamber, and a return current passage under the latter, support means for said casing, supply means in communication with said crushing chamber, for supplying material therein, crushing elements within said crushing chamber, for crushing said material, operator means for operating said elements, blower means in communication with said passage and adapted to circulate a separating fluid current up through, out over, and down around, said crushing chamber and in through said return current passage, for floating fine material into said settling chamber, bottom wall means for said return current passage, below the latter and within and spaced from said cas-

ing, particle interceptor means around said bottom wall and extended vertically across said return current passage, for intercepting particles floating in said current toward said return current passage and dropping said particles into said settling chamber, and rotatable shelf means around said wall means and extended therefrom below and adjacent and across said interceptor means, adapted to receive and to rotatably discharge said particles precipitated therefrom toward said settling chamber, and to resist current leakage between said wall means and said interceptor means.

10. In a pulverizer, a casing enclosing a crushing chamber having an outlet for fine material and a dropper outlet for coarser material, support means for supporting said casing, supply means for supplying material to be crushed in said chamber, comprising a vertical conduit in communication with said chamber, for vertically precipitating coarser material there toward, and a lateral conduit in communication with one side of said vertical conduit, for laterally supplying uncrushed material thereto at said side thereof, crushing elements within said chamber for crushing said material, and operator means for operating said elements; the combination therewith of an adjustable inner wall for said vertical conduit within and at the other side thereof, opposite and spaced from said lateral conduit, adapted to laterally sustain opposite the latter said coarser material precipitated through said vertical conduit, and adjustable relatively to said lateral conduit for varying said sustenance.

11. A current pulverizer comprising, a casing enclosing a crushing chamber having an upper current outlet and a lower current inlet, support means, supply means for distributing material to be crushed therein, crushing elements within said chamber, operating means for said elements, blower means upfloating fine material from said elements and permitting coarser material to drop therefrom, said chamber having below said elements an open dropper outlet for dropping coarser material through said current to below the zone thereof and externally of said chamber, and coarser material discharge means below said dropper outlet, in communication therefrom below the zone of said current to and extended externally of said casing.

12. In a pulverizer comprising, an annular casing rotatable around a substantially vertical axis and enclosing a crushing chamber having an upper current outlet and a lower current inlet, supply means distributing material to be crushed in said chamber, crushing elements within said chamber, operator means for said elements, blower means upfloating fine material from said elements and permitting coarser material to drop therefrom, said chamber having below said elements an open dropper outlet dropping coarser material through said current to below the zone thereof and to externally of said chamber, coarser material discharge means below said dropper outlet, in communication therefrom below the zone of said current to and extended externally of said casing, rotary means rotating said casing, and support means for said parts; the combination therewith of a rotation connection between and rotatable with said rotary means and said casing, disposed entirely above the zone of said distribution, connected to said casing above said zone, and constructed and arranged to rotate said casing from said rotary means from above

said zone, and from without and above the space below said dropper outlet.

13. In a current recirculation pulverizer comprising, a casing enclosing a return current passage, means spaced within said casing enclosing a crushing chamber having an upper current outlet and a lower current inlet in communication with said passage and affording therewith an endless current passage up through and down around said crushing chamber, supply means distributing material to be crushed in said crushing chamber, crushing elements within said crushing chamber, operator means for said elements, blower means upfloating fine material from said elements and permitting coarser material to drop therefrom, said chamber having below said elements an open dropper outlet above said return current passage, for dropping coarser material through said current to below the zone thereof and externally of said chamber, and support means for said parts; the combination therewith of coarser material discharge means below said dropper outlet and below said return current passage, in communication therefrom below the zone of said current to and extended externally of said casing, comprising a rotatable bottom wall below and for said return current passage, opposite and spaced below said dropper outlet a distance equal to the height of said return current passage, in communication from the latter to externally thereof, and constructed and arranged to receive said dropped material below said return current passage and to rotatably discharge it from thereunder to externally thereof.

14. In a current recirculation pulverizer comprising, a casing enclosing a return current passage, means spaced within said casing enclosing a crushing chamber having an upper crushed material outlet and a lower uncrushed material dropper outlet in communication with said passage and affording therewith an endless current passage up through and down around said crushing chamber, supply means for material to be crushed in said crushing chamber, crushing elements within said crushing chamber, blower means for upfloating crushed material from said elements, discharge means opposite and below said dropper outlet, and below said return current passage, in communication from below the latter to externally of said casing, operator means for said elements, and support means for said parts; the combination therewith of uptosser means inwardly of and below said dropper outlet, spaced a distance above said discharge means, in communication from said spaced distance above the latter up through said dropper outlet and with said elements, and constructed and arranged to return to the latter from said distance above said discharge means material on the latter above said distance, and to limit the discharge by said discharge means to material on the latter below said distance.

15. In a current recirculation pulverizer comprising, a casing enclosing a return current passage, an annular crushing die rotatable around a substantially vertical axis, spaced within said casing and having an inner annular crushing face enclosing a crushing chamber having an upper crushed material discharge outlet and a lower uncrushed material dropper outlet in communication with said passage and affording therewith an endless current passage up through and down around said chamber, supply means for the distribution of material to be crushed in

said chamber, a rotatable crushing roll within and eccentric of said die and having a peripheral crushing face reciprocal to said face for crushing said material between said faces, rotatable blower 5 means for upfloating fine material from said faces and permitting coarser material to drop therefrom, and externally extended discharge means for said uncrushed material below said return current passage and opposite and spaced 10 below said dropper outlet a distance equal to the height of said return current passage, and in communication from below the latter to externally of said casing, and support means for said parts; the combination therewith of rotary means 15 above and for rotating said die, disposed above the zone of said distribution, and entirely without the space between said dropper outlet and said discharge means, connected to said die above said zone, and constructed and arranged to rotate said die from above and entirely without 20 said space.

16. In a pulverizer comprising, a horizontal die

rotatable about a substantially vertical axis and having an inner annular crushing face enclosing a crushing chamber having an upper fine material discharge outlet and a lower uncrushed material dropper outlet, a rotatable crushing roll 5 within and eccentric of said die, having a peripheral crushing face cooperable with said face, for crushing material between said faces, supply means for distributing material to be crushed to said faces, and support means for said parts; 10 the combination therewith of means for rotating said die having circumferentially spaced discharge passages above the zone of said distribution, above said annular face and extended across said upper outlet, connected to said die 15 above said zone, entirely above said dropper outlet, and constructed and arranged to pass said discharge from above said zone, and to rotate said die from above the latter and from above and entirely without the space below said dropper 20 outlet.

GEORGE HOLT FRASER.
